5 Claims. (Cl. 179—1)

1

In two-way loud speaker telephone installations using two amplifiers, the Larsen effect is generally eliminated by systems blocking one of the two amplifiers whilst the other works.

This result is nearly always obtained by polarizing beyond the "cut-off" one of the amplifier valves to be eliminated, the blocking polarization being itself obtained from the modulation amplifier fed by the amplifier which works, and rectified.

This presumes that in the absence of conversation the two amplifiers are free, and consequently there is a risk of setting up the Larsen effect due to the reaction of one amplifier on the other through the intermediary of the microphones and loud speakers.

It is therefore necessary that the gain be reduced from the level capable of bringing about the setting up of the said effect. In practice, it is found that the power available for conversation with such a system is quite insufficient. It is therefore indispensable to introduce auxiliary circuits for reinforcing the audition at the moment when, one of the amplifiers being blocked, the other can work without fear of setting up the Larsen effect.

Different methods are resorted to which all use a variation of the polarization of the valves of variable gain, the said variation of polarization being obtained, for example, by the suppression of the plate current of the output valve blocked beyond the "cut-off" or by the blocking of a high frequency oscillator the rectified high frequency of which serves precisely for polarizing a valve of the amplifier in order to reduce the gain in the absence of modulation.

These methods, however, are imperfect or too complicated to permit of economical exploitation. In particular, the variations of polarization introduced on the grids of valves of high gain can cause disturbances which are partially eliminated by push-pull amplifiers of small economy. The obtaining of the polarization at the return of the anodic current demands careful filtration in order to eliminate all trace of enlargement. For its part, this careful filtration introduces time constants which are troublesome. The blocking of the amplifier by the output valve causes this to work in more or less linear parts of the characteristic curves, and distortions which are not negligible ensue and alter the fidelity of the reproduction. Finally, this method requires the employment of two distinct feeds, one for each amplifier, and also of important blocking tensions.

The object of the present invention is to eliminate all the aforesaid drawbacks.

2

In accordance with the invention, the blocking is no longer done by the output valve which can therefore work to stable characteristics with all the fidelity desirable. In the first mode of carrying out the invention, the blocking is done by the aid of a special valve and by a non-active electrode of this valve specially reserved for the purpose. In this manner, it is no longer necessary to provide a push-pull amplifier and there is no risk of mixing modulations of the two amplifiers, without complicated filters.

The over-amplification after blocking is no longer obtained by variations of grid polarization but by variation of cathode potential which gives the same practical result but requires very small current variations and no longer requires two anodic feeds. A great efficiency is thus obtained with very simple means. Moreover, the necessary blocking tension is small and this reduces the time constants for obtaining over-amplification.

In a second mode of carrying out the invention a slightly different principle is used giving analogous results with similar advantages but with means somewhat more complex. Instead of blocking an amplifier valve, the excitation of the loud speakers is acted upon through a power valve which is used to control the speaker excitation. The blocking tension is applied to the grid of the valve and the screen tension is stabilized in such manner as to give a more rapid disappearance of the plate current. When the plate current of the excitation valve is annulled, a more elevated tension appears on the plate. If the initial tension is, for example, 100 volts this becomes 200 volts upon the disappearance of the plate current by reason of the fall of tension which then disappears in the excitation winding. This important increase in tension arising from blocking is taken advantage of for obtaining an over-amplification effect. It suffices, for this purpose, to feed the preamplification valves and the screen of the power valve across the excitation winding to cause them to pass from a slight gain to an elevated gain.

The annexed drawings illustrate diagrammatically several examples of the aforesaid two modes of carrying out the invention.

Figure 1 is a simplified diagram of a known telephonic installation wherein the amplifier of the line not used is blocked by the rectified amplified modulation coming from the amplifier of the line in use.

Figure 2 is a diagram of one line according to

the first mode of carrying out the invention, the second line being identical therewith.

Figure 3 illustrates a variant in which the special valve is replaced by two valves of more standard type.

Figure 4 is a diagram of a complete assemblage.

Figure 5 illustrates another variant in which the functions of amplification are separated from the modulation and amplification of rectification, thus permitting an independent regulation of the blocking circuit, which advantage is very important in practice when noises foreign to the conversation threaten to disturb the functioning of the apparatus.

Figure 6 is a diagram of the second mode of carrying out the invention.

In Figure 1 the known installation comprises two stations P and P¹ connected together by two distinct lines each comprising a microphone and a loud speaker respectively M and HP and M¹ and HP¹. Between M and HP¹ and between M¹ and HP are interposed respective amplifiers A and A¹. When P speaks, the amplified modulation from A is rectified by D and serves for blocking A¹. Similarly, the modulation from A¹ rectified by D¹ blocks A when P¹ takes over the speech. The Larsen effect is thus avoided in a measure but such an installation has the drawbacks above referred to and to avoid these it is necessary to adopt an installation of the kind illustrated in Figures 2 to 5 or 6.

In Figure 2 only a single way or line is illustrated but it will be understood that the second line is identical therewith. Current from the microphone M is transmitted by the transformer T¹ to the grid G¹ of the first valve L¹ of a two-valve amplifier L¹L². The valve L¹ is a heptode comprising a triode element and a tri-grid element with a common cathode. The anode of the tri-grid element is connected by a condenser C¹ uncoupled by two resistances R² and R³ to the first grid G⁵ of the second valve L² of the amplifier, which second valve is a tetrode with grid screen. The plate current from L² feeds the primary of a three-winding transformer T², one secondary of the latter feeding the loud speaker HP¹ of P¹ and the other secondary feeding a full wave rectifier D¹. The negative tension produced by D¹ is filtered by the condenser C² in parallel with the resistance R⁴ and is transmitted on the one hand to the grid G² of L¹ and, on the other hand, to the grid in the second line corresponding to the grid G³ of valve L¹, which grid, if the second line had been illustrated, would have been designated G¹ and its valve L¹. In Figure 2, the connection to the second line is indicated by the legend "pol. 2." The cathode of L¹ is earthed through a resistance R¹, whilst the grid G³ of the tri-grid element is fed by the negative tension coming from the rectifier (which would be D¹) of the second line (that is to say coming from the amplified and rectified modulation produced when P¹ takes over the speech). The connection of G³ to the second line is indicated by "pol. 1" in Figure 2. The last grid G⁴ of L¹ is a simple grid screen like G⁶ of L².

The operation of the installation is as follows:

When P speaks, the current from M is transmitted by T¹ to L¹ which amplifies it, then to L² which further amplifies, and passes to T² which actuates the loud speaker HP¹. At the same time, however, the modulation from T² is rectified by D¹ and the negative impulse from D¹ acquires the desired time constant at the same time that it is filtered by C², R⁴. This

negative tension applied to G¹ of L¹ is effective for blocking the amplifier A¹ of the second line for cutting off the current of the plate of L¹. On the other hand, the same tension applied to G² of L¹ causes the anode current I₁ of the triode element to disappear. This current, which traverses the resistance of the cathode R¹ common to the triode elements and tri-grid, gives at the start an important polarization to the tri-grid element which then amplifies very little. When the current I₁ disappears, there no longer remains the anode current I₂ of the tri-grid element to traverse R¹ and the tri-grid element, little polarized, then amplifies strongly. There is thus obtained the desired over-amplification for the speech transmitted from P to P¹, at the same time that the amplifier A¹ of the non-utilized line between P¹ and P is put out of service. The two circuits are symmetric so that the operation is the same when P¹ takes over the speech and A is then put out of service.

The time constants given by C² and R⁴ (or by C¹ and R⁴ not shown) are such that between two words or two syllables the amplifiers recover their initial characteristics of small gain and permit the speakers to interrupt one another.

In Figure 2 a heptode of the type ECH21 is used as the valve L¹. In Figure 3 a variant is shown wherein the said valve is replaced by a triode L¹ and a pentode L², for example respectively of the types 6J3 and 6L7. The connections are the same, the two cathodes being earthed by a common resistance R¹.

In Figure 4 a two line installation is shown having the connections of Figure 2. In this case, however, there are two half wave rectifiers D² and D¹, and moreover the modulation rectified by D² or D¹, after traversing the filter C², R⁴ or C¹, R⁴, traverses a second filter C⁴, R⁸ or C¹⁴, R¹⁸ before reaching the grids G² and G¹ or G² and G³. This second filter eliminates the alternative component which could remain after rectification.

In Figure 5 a variant is illustrated wherein recourse is had to a special amplifier A¹ the current of which is rectified by the rectifier D¹, instead of taking the modulation at the outlet of T².

The connections of the valves L¹ and L² is generally the same as before, but the resistance R³ is here replaced by a potentiometer R⁵. The amplifier A¹ is composed of a pentode L³ and a triode L⁴. In this amplifier, the first grid G¹ of the valve L³ is connected in shunt at the outlet of the secondary of the transformer T¹, and the grid G³ of L¹ is connected to the corresponding grid G⁸ of L³.

The plate current of L³ is transmitted, through the intermediary of a condenser C³ uncoupled by the resistance R⁶ and the potentiometer R⁷, to the grid G¹⁰ of L⁴. The anode current of L⁴ feeds the primary of a transformer T³ the secondary of which controls the rectifier D¹ which transmits the rectified modulation on the one hand to G² of L¹ and on the other hand to G¹ of L¹ in the other line (indicated by "pol. 2" in Figure 5). The grid G⁹ of L³ is a simple grid-screen. Finally the valve L² is connected to the loud speaker HP¹ through the transformer T² as before.

In these conditions, the regulation of the power in the loud speaker HP¹ can be effected by the potentiometer R⁵, and the regulation of the blocking action is done by the potentiometer R⁷. The

operation of the installation is the same as that in Figure 2. The amplifier A¹ can also be constituted by a valve identical to L¹; the essential thing is that the gain of the system must be sufficient for procuring after rectification the necessary tension for blocking the principal amplifier of the line not used and for freeing the over-amplification in the line used. However, it should be noted that the grid G₈ of L₃ must obligatory be connected to G₃ of L₁; in effect, G₈ serves to block L₃ and if L₃ were not blocked at the same time as L₁, the modulation emitted by HP¹ and striking M¹ would arrive at D¹ which would have for effect to block the amplifier L₁, L₂ from the line in service.

Figure 6 illustrates a second mode of carrying out the invention wherein that valve is blocked which controls the excitation of the loud speaker in the line not used. In this case the amplifiers A and A¹ (valves L₅, L₆ and L¹₅, L¹₆) are of standard type. L₅ and L₆ are two bigrids. The secondary of the transformer T¹ fed by the microphone M is connected to the first grid G₁₁ and through the filter R₉, C₅ to the second grid G₁₂ of L₅. The grid G₁₂ is connected through a resistance R₁₀ to the anode circuit of L₅ and the coupling between L₅ and L₆ is done by a condenser C₆ and the resistances R₁₁, R₁₂ as in the case of the valves L₁, L₂. The anode current from L₆ passes through the primary winding of a three-winding transformer T₂ and one of the secondaries feeds the loud speaker HP¹. The other secondary feeds the rectifier D₂ by way of a valve L₇ which can be blocked by the same tension as that which blocks the valve L¹₈ (not shown) which is the exciter of the corresponding loud speaker. The valve L₇ is a pentode, its first grid G₁₇ being connected to a terminal of the transformer T₂ and its second grid G₁₈ being connected on the one hand to the outlet of the second rectifier D¹₂ (not shown) and on the other hand to the grid G₁₅ of the valve L¹₈ aforesaid. The third grid G₁₉ of L₇ is a simple grid-screen. The modulation leaving the filter C₂, R₄ is transmitted on the one hand to the grid G₁₅ of the valve L₈ which controls the winding E which excites the loud speaker HP and on the other hand to the grid G₁₈ of the second line valve L¹₇ identical to the valve L₇. L₈ and L¹₈ are bigrids, the grid G₁₆ or G¹⁶ being simply a grid-screen. The anode current from L₈ is transmitted on the one hand to the winding E and on the other hand to the point O to which are also connected the grid G₁₂ and the anode of L₅ and the grid G₁₄ of L₆. The winding E is connected to the general high tension feed + 200 v. as also is the winding E¹ exciting HP¹. This latter winding is connected on the one hand to the point O¹ corresponding to O and on the other hand to the anode of the valve L¹₈. These different valves and connections have not been shown in order to simplify the drawing.

This installation operates as follows:

If a person at P speaks into M, the amplifier A, at the same time that it feeds HP¹, gives (as in Figures 1 and 2) a derivation towards D₂ which procures the blocking tension. This tension is applied to the grid G₁₅ of L₈ so that when M speaks L₈ is blocked to the cut-off and the excitation current of HP disappears. HP should then be mute. At the same time that the fall of tension in the excitation winding disappears (it is about 100 volts in practice) the corresponding tension at O passes from 100 to about 200 volts and this increase in tension applied to the

grids G₁₂ and G₁₄ and to the anode of L₅ in the amplifier at work procures the desired over amplification.

The valve L₇ should be able to be blocked at the same time as HP¹ in order to avoid that the modulation reaching D₂ blocks the amplifier A in service. That is why L₇ is connected to L₈ which assures the blocking of the excitation of HP¹.

10 Further, the same results should be obtained by shunting L₇ and D₂ upon L₅ and not upon L₆, thereby using a connection analogous to that of Figure 5.

Of course it would also be possible to use a 15 full-wave rectifier D₁ or D¹₁ instead of a half wave rectifier D₂ or D¹₂, the connections being then the same as in Figures 2 and 5.

The two lines being symmetrical, the operation is the same when P¹ takes over the speech.

20 As in the first mode of carrying out the invention, the time constants of the circuits should be chosen so as to permit the speakers to interrupt one another.

I claim:

25 1. A two-way loud speaker installation comprising a pair of transmission lines respectively including a loud speaker, a microphone, and a circuit connecting said microphone to said loud-speaker, said circuit having an amplifying means therein comprising a first grid including means coupled to said microphone for modulating the output of said amplifying means, means including a second grid operable upon energization thereof for increasing the gain of said amplifying means, and means including a third grid operable upon energization thereof for biasing said amplifying means to cut-off, and a control means including a rectifier for generating a biasing control voltage in response to modulation of said amplifying means by said first grid, and circuits interconnecting each of said lines with the other including means for applying the control voltage generated by the control means in either of said lines to the first grid in such line and to the third grid in the other of said lines.

30 2. A two-way loud speaker installation comprising a pair of lines respectively having a microphone, a first transformer having energizing means connecting it to said microphone, an amplifier including a modulation grid having means connecting it with said transformer, means including a blocking grid operable upon energization for rendering the amplifier inoperative, and means including an over-amplification grid operable upon energization to increase the gain of the amplifier, a second transformer having means connecting it to the output of the amplifier, a loud speaker connected to said second transformer for operation thereby, and control means including a rectifier for producing a biasing control voltage in response to operation of said amplifier, and circuit means interconnecting said lines for applying the biasing control voltage from the control means in either of said lines to the over-amplification grid in such line and to the blocking grid of the other line.

35 3. A two-way loud speaker telephone installation comprising a pair of lines respectively having a microphone, a first transformer having energizing means connecting it to said microphone, means connected with said first transformer for amplifying signals to be transmitted comprising an electronic valve having an output circuit, a first control grid including means con-

nected to said transformer for controlling the energization of said output circuit, a second grid operable upon energization thereof for biasing said valve to cut-off, and third grid operable upon energization thereof for increasing the gain of said valve, a second stage of amplification having a control grid including means connecting it to said output circuit, a loud speaker having transformer means connecting it to said second stage for operation thereby, and means including a rectifier for producing a biasing control voltage in response to the transmission of signals over the line in which it is located, and a control circuit interconnecting said lines and including means for applying the biasing control voltage produced in either of said lines to the third grid in the line producing such voltage and to the second grid in the other of said lines.

4. A two-way loud speaker telephone installation comprising a pair of lines respectively having a microphone, a first transformer having energizing means connecting it to said microphone, amplifying means comprising a triode having a control grid, an electronic valve having first and second control grids, and a common cathode circuit means for said triode and valve, energizing means for said valve including a connection for said first control grid with said transformer, an output circuit having energizing means connected to said valve and a second transformer energized by said output circuit, a loud speaker having an energizing circuit connecting it with said second transformer, and control means including a rectifier for producing a biasing control voltage in response to the transmission of signals over the line in which it is located, and circuit means interconnecting

said lines for applying the biasing control voltage produced by the control means in either of said lines to the triode control grid in such line and to the second control grid of the electronic valve in the other of said lines.

5. A two-way loud speaker installation comprising a pair of transmission lines respectively having an amplifying means therein, each of said amplifying means including a control means operative in response to the reception of a signal to be transmitted for operating it to amplify such signal, a regulating means operable upon energization to increase its gain, and a blocking means operable upon energization to render it inoperative to amplify, each of said lines further having means responsive to operation of its amplifying means by its control means for producing a biasing control voltage, and circuit means interconnecting said lines for applying the biasing control voltage produced in either of said lines to the regulating means in such line and to the blocking means in the other of said lines.
